UNITED STATES PATENT OFFICE.

TYCHO VAN ALLER, OF SCHENECTADY, NEW YORK, ASSIGNOR TO GENERAL ELECTRIC COMPANY, A CORPORATION OF NEW YORK.

ELECTRIC SOLDERING-IRON.

No. 825,251.

Specification of Letters Patent.

Patented July 8, 1906.

Application filed July 3, 1905. Serial No. 228,925.

To all whom it may concern:

Be it known that I, TYCHO VAN ALLER, a subject of the King of Denmark, residing at Schenectady, county of Schenectady, State of New York, have invented certain new and useful Improvements in Electric Soldering-Irons, of which the following is a specification.

Thus invention relates to soldering-irons and the like which are heated by an electric current; and its object is to improve and simplify the construction and at the same time increase the efficiency of such a device.

The invention consists in the combination, with a suitable tip having one or more recesses in its sides, of coils of wire housed in said recesses and covered with a heat-insulating substance. The coils are preferably connected in series, and current is led to them by means of flexible conductors passing through a tubular handle.

In the accompanying drawings, Figure 1 is a longitudinal elevation of a soldering-iron embodying the present invention. Fig. 2 is a view of the tip with the heat-insulating covering removed. Fig. 3 is a rear view of the tip removed from the handle and shown on a larger scale than Figs. 1 and 2. Fig. 4 is a longitudinal sectional elevation of the tip and the heating elements. Fig. 5 is a plan view of one set of coils and the case in which they are packed; and Fig. 6 is a cross-section on the line 6-6, Fig. 4.

The handle 1 is made of wood or some other suitable insulating material. It is tubular and carries a metallic shank 2, which is preferably perforated, as shown, for the sake of ventilation. At the end of the shank is a head 3, having lugs 4, which are drilled and tapped to receive the screws 5, which pass through flanges 6 on a plate 7, to which the tip 8 of the soldering-iron is secured by the screws 9. The tip has a tapering point 10, and its body is cut away on one or both sides 45 to form a recess or recesses, leaving a flat shank 11, whose width is the same as the rest of the tip, but whose thickness is preferably about one-third that of the tip.

In each recess is a plurality of heating-coils 12, composed of fine wire, offering considerable resistance to the passage of an electric current. The coils are insulated from each other and from the shank of the tip by strips

13 of insulation. They are, furthermore, inclosed in a sheet-metal case 14, having an open bottom and provided with lugs 15, which extend down over the edges of the shank 11 and are secured thereto by screws 16, the lugs on each side overlapping, so that one screw will fasten both of them. These cases are lined with insulation to prevent the coils from coming in contact with them or with the tip. The coils in each case are connected in series, and their terminals 17 project through holes in the plate 7 into the space between said plate and the head 3. A sheet of insulation 18, such as mica, is laid on the plate 7 under the binding-nuts 19 on said terminals, and one terminal in each set of coils is connected with one of the flexible conductors 20, which pass through the tubular handle and shank 2. The other two terminals are cross-connected by a short conductor 21.

A heat-resisting covering 22, of asbestos or the like, is applied to the outside of the cases and the shank 11, and this covering is held in place by a jacket 23, of sheet metal, having flanges 24, which enter the narrow spaces 25 between the tip and the ends of the cases 14. The rear end of the jacket is secured to the head 3, preferably by the screws 5, as shown.

When an electric current is passed through the coils, they become highly heated and impart their heat to the tip very readily by reason of their close proximity to the shank 11. All radiation of heat is prevented by the cases, the asbestos covering, and the jacket. I do not desire to restrict myself to the particular form or arrangement of parts herein shown and described, since it is apparent that they may be changed and modified without departing from my invention.

What I claim as new, and desire to secure by Letters Patent of the United States, is—

1. In an electric soldering-iron, the combination with a tip having one or more recesses in its sides, of heating-coils located in said recesses,

2. In an electric soldering-iron, the combination with a tip having one or more recesses in its sides, of heating-coils located in said recesses, and means for inclosing said coils.

3. In an electric soldering-iron, the combination with a tip having a recess in its side, of heating-coils in said recess, and a case for

said coils having an open bottom and secured to said tip.

4. In an electric soldering-iron, the combination with a tip having a recess in its side, of 5 heating-coils in said recess, and a case for said coils having an open bottom and lugs secured to said tip.

5. In an electric soldering-iron, the combination with a tip having a recess in its side, of 10 heating-coils in said recess, a sheet-metal case inclosing said coils and secured to said tip, and strips of insulation between said coils and between the coils and the case and tip.

6. In an electric soldering-iron, the combination with a tip, of heating-coils, a case inclosing said coils, and a covering of heat-resisting material outside of said case.

7. In an electric soldering-iron, the combination with a tip having a recess in its side, of 15 heating-coils in said recess, a case inclosing

said coils, and a covering of heat-resisting material outside of said case.

8. In an electric soldering-iron, the combination with a tip, of heating-coils, a case inclosing said coils, a covering of heat-resisting material outside of said case, and a jacket for said covering.

9. In an electric soldering-iron, the combination with a tip, of heating-coils applied thereto, a plate secured to the shank of said tip and having flanges, and a handle having a head provided with lugs secured to said flanges.

In witness whereof I have hereunto set my hand this 30th day of June, 1905.

TYCHO VAN ALLER.
